CLAIM

The ornamental design for a beverage mug, as shown and described.

DESCRIPTION

FIG. 1 is a top right perspective view of the beverage mug;

FIG. 2 is a top plan view thereof;

FIG. 3 is a rear elevational view thereof;

FIG. 4 is a front elevational view thereof;

FIG. 5 is a bottom plan view thereof;

FIG. 6 is a right side elevational view thereof;

FIG. 7 is a left side elevational view thereof; and,

FIG. 8 is an exploded top right perspective view illustrating the insert and cap features of the beverage mug.

The broken lines shown in the drawings are directed to environment and are for illustrative purposes only; the broken lines form no part of the claimed design.
